OUTLET BOX AND ANCHOR THEREFOR

Clyde Fredriksen, Gurney, Wis.

Application June 14, 1944, Serial No. 540,345

1 Claim. (Cl. 220—3.6)

1

The invention relates to a junction box, and more especially to outlet boxes for electrical switches and receptacles.

The primary object of the invention is the provision of a box of this character, wherein it can be readily and easily secured in place within a wall opening, with dispatch, and without regard to the thickness of the wall having the opening for the box, the latter being held firm and secure when within the opening.

Another object of the invention is the provision of a box of this character, wherein the anchoring adjuncts thereto are a part of the said box when distributed by the maker or tradesman, and such box can be slipped into place within a wall opening without damaging the wall fabrication, and can be anchored thereto within the least possible time, and requiring minimum labor for so doing.

A further object of the invention is the provision of a box of this character, wherein the anchoring thereof is accomplished without the same, so that the inside dimensions are undisturbed, thereby providing adequate space for installation of fixtures therein, the box being held fast.

A still further object of the invention is the provision of a box of this character, which is simple in construction, thoroughly reliable and efficient in its purposes, strong, durable, easily set in place with dispatch, it being resistant to outward pull thereon, and inexpensive to manufacture and install.

With these and other objects in view the invention consists in the features of construction, combination and arrangement of parts as will be hereinafter more fully described, illustrated in the accompanying drawing, which shows the preferred embodiment of the invention, and pointed out in the claims hereunto appended.

Figure 1 is a front elevation of a junction box constructed in accordance with the invention, showing by dotted lines the normal position of the anchoring medium, while by full lines is shown the anchoring medium being moved to a clamping position.

Figure 2 is a fragmentary vertical sectional view through a wall opening showing the box placed therein, the anchoring medium being shown by full lines in anchoring position and by dotted lines in normal released position.

Figure 3 is a sectional view taken on the line 3—3 of Figure 2 looking in the direction of the arrows.

2

Figure 4 is a perspective view of one of the anchoring wings detached.

Similar reference characters indicate corresponding parts throughout the several views in the drawing.

Referring to the drawing in detail A designates generally a junction or outlet box, having its body 10 of the ordinary well known construction, which at opposite end walls 11 thereof at the open front of such box are the outturned inner and outer ears 12 and 13, respectively, the outer ears 13 being adaptable for fasteners 14 which secure the said box to the wall 15 at the outer face thereof, while the inner ears 12 are for fasteners, not shown, to detachably secure cover plate, not shown, over the front opening to the box, the electrical switch or receptacle, not shown being housed as usual within the said body 10 of the box.

The wall 15 is formed with a suitable opening 16 into which is slipped the body 10 of the box A, which is the ordinary way of placing the latter in place. The side walls 17 of the body 10 at the open front thereof is provided with out turned ears 18, in which are received loose threaded bolts 19, being rather long, or of a length slightly greater than the depth of the body 10, and are in threaded connection with anchoring wings 20, the bolts 19 being formed with rivet heads 21 at their inner ends, while the outer ends of such bolts are provided with screw driver receiving heads 22. Normally the wings 20 which are adapted for lateral off-setting outwardly from the sides or walls 17 of the body 10, are turned inwardly against the bottom 23 of the latter, to overlap such bottom, until the body 10 has been fully inserted in the wall opening 16, and thereafter on turning the bolts 19 the said wings 20 are thrown outwardly, clearing the side walls of the body 10, so that they may be clamped against the inner face of the wall 15. In this manner the body 10 of the box is firmly and securely anchored to the wall 15 for confinement within the opening 16 therein, as will best be seen in Figures 2 and 3 of the drawing.

The rivet heads 21 function to retain the wings 20 on the bolts 19, and also through friction will tend to cause the turning of the wings off and from the bottom 23, which is the normal position of such wings, to bring these clear of the side walls 17 of the body 10 to have them come to clamping position against the wall 15 at its inner face, as will be clearly seen in Figures 2 and 3 of the drawing.

The manner of anchoring the body 10 is effec-

tive to resist an outward pull thereon, to which it is often subjected, and the anchorage is as strong as the material to which it is secured.

The anchorage can be had with varying thicknesses of wall structures, and is firm and secure.

What is claimed is:

A box of the kind described, comprising a body having an open front, an end wall and side walls, attaching ears carried by the open front, a second set of short ears carried by 10

the open front, bolts screwed through said short ears and extending beyond the end of the body and having heads, wide thin wings threaded on said bolts and prevented from passing from the bolts by the heads, said wings being normally held inwardly against the face of the end wall of the body and turnable outwardly to operative position by said bolts.

CLYDE FREDRIKSEN.
